DRAFT RIGGING

Donald S. Barrows, Rochester, N. Y., assignor to
The Symington Company, New York, N. Y., a
corporation of Maryland

Application June 23, 1930. Serial No. 463,172

10 Claims. (Cl. 213—50)

This invention relates to draft rigging for railway rolling stock, and more particularly to an improved form of articulated coupler stem and associated vertical yoke.

- 5 The principal object of my invention, generally considered, is to provide an articulated coupler stem of such a construction that it may be interchangeably used with a standard horizontal yoke, or a vertical yoke interchangeable
10 with a standard vertical yoke, and to so design such a yoke with a hooded front end that it may be employed with draft lugs in which the general dimensions and strength are equivalent to those of the standard draft lugs employed with
15 standard vertical yokes, said yoke and the associated draft lugs being formed to interfit for the purpose of providing the necessary increase in hood width for the reception of the articulated coupler stem.
- 20 Another object of my invention is the provision of a swivel butt coupler and vertical yoke adapted to be connected by a horizontal key and used between normally spaced draft sills in combination with front draft lugs of generally
25 normal width, said yoke being interchangeable with a standard vertical yoke such as used with a rigid shank coupler, and the coupler being adapted for use with a standard horizontal yoke, the coupler butt for that purpose having side
30 extensions or portions increased in width adjacent the rear ends of the key slot therein for increasing the key bearing area, the yoke having the side walls of the hooded portion thereof increased in thickness adjacent the rear ends
35 of the key slots therein and extended rearwardly at the same points, the associated front draft lugs being correspondingly notched to receive said extensions without decreasing the general width thereof.
- 40 A further object of my invention is to provide a swivel butt coupler connected to the hooded front end of an associated yoke by a horizontal key, in combination with front draft lugs in which the stop faces are normally disposed rearwardly of the rear edge of the yoke hood, the slots in the yoke and coupler receiving the key being such that the coupler moves rearwardly relative to the key, the key moves rearwardly relative to the yoke, and on full compression of the associated gear the yoke moves rearwardly relative to the draft lugs, said lugs being notched to receive the adjacent portions of the side walls of the yoke hood upon such rearward movement.
- 45 A still further object of my invention is the provision of a striking casting, sill tie member and slotted front draft lugs in which the lugs are integral with, or adapted to be securely connected to, a combined striking casting and sill tie member, and the lug shoulders forming the front stop means for the associated front follower are notched to cooperate with a specially formed vertical yoke and associated swivel block of a co-operating articulated coupler stem, the notched portions of said shoulders being reinforced by flanges extending along the upper and lower edges of the slots therein and merging into the inner faces of the lugs, the loss of said reinforcements being compensated for, if desired, by tapering flanges extending from the outer faces of the lugs and received in the cooperating sill slots, said lugs, if integral with the combined striking casting and sill tie member, being desirably further reinforced by flanges extending from the outer faces thereof along the inclined lower edges to the sill tie member, starting a short distance below the lower ends of said lugs so as to overlap tapering reinforcements on the inner faces thereof.
- 50 An additional object of my invention is to so design a swivel butt coupler and connected vertical yoke that they are adapted for application between normally spaced sills of a railway vehicle and disposed either with the center line of draft at normal elevation, or raised so that said center line corresponds with the height of the neutral axis of the draft sills, the yoke, at the same time, being constructed so that it is interchangeable with a standard vertical yoke, and the swivel butt coupler being so designed that it is also adapted for use with a standard horizontal yoke.
- 55 Other objects and advantages of the invention relating to the particular arrangement and construction of the various parts will become apparent as the description proceeds.
- 60 Referring to the drawings illustrating my invention, the scope whereof is defined by the appended claims:—
- 65 Figure 1 is a partial side elevation and partial longitudinal section of a coupler and associated vertical yoke assembled with the draft sills and other parts of an associated railway vehicle underframe.
- 70 Fig. 2 is a partial plan and partial horizontal sectional view of the coupler, yoke and parts of the underframe shown in Fig. 1.
- 75 Fig. 3 is a transverse sectional view on the line 3—3 of Fig. 1, looking in the direction of the arrows, shown on an enlarged scale.
- 80 Fig. 4 is a fragmentary longitudinal vertical

sectional view of the front end of the vertical yoke.

Fig. 5 is a fragmentary sectional view on the line 5—5, Fig. 4, looking in the direction of the 5 arrows.

Fig. 6 is a vertical longitudinal sectional view of the novel form of combined striking casting, sill tie member and slotted draft lugs detached from the draft sills and associated parts of the 10 railway vehicle.

Fig. 7 is a fragmentary view, similar to Fig. 6, but showing a modification.

Fig. 8 is a fragmentary sectional view of another form of pivotal connection between the 15 coupler stem and associated swivel block.

Fig. 9 is a fragmentary vertical longitudinal sectional view of a construction corresponding to Fig. 1, but showing a modification, the associated coupler being shown partly in side elevation.

Fig. 10 is a partial plan and partial horizontal sectional view of the coupler, yoke and parts shown in Fig. 9.

Fig. 11 is an end elevation of the striking casting and sill tie member.

Fig. 12 is a transverse sectional view on the line 12—12 of Fig. 10, looking in the direction of the arrows.

Referring to the drawings in detail, like parts 30 being designated by like reference characters, and first considering the embodiment of my invention shown in Figs. 1 to 6, inclusive, there is shown the stem or shank 1 of a swivel butt coupler, or one having a two-part or articulated stem. The swivel block or butt portion 2 of the articulated stem is connected to the coupler shank by pivotal means 3 which, in the present embodiment, take the form of a pair of similar pivot pins 4 which extend through the shank 35 loops or rearwardly extending flanges or webs 5 and 6 on the coupler stem and intercalated flanges or webs 7, 8 and 9 on the swivel block.

As is usual in swivel butt couplers of the type illustrated, the shank loops 5 and 6 desirably 45 have their rear edges formed cylindrical and coaxial with the apertures 10 therein for receiving the associated pivot pins 4, which edges engage correspondingly curved pocket portions 11 and 12 on the swivel block 2 for transmitting 50 buffing forces, while permitting the desired angling therebetween. The corresponding edges of the flanges 7, 8 and 9 are desirably curved coaxial with the corresponding pin-receiving apertures and fit into a correspondingly curved pocket 55 13, and closely approach correspondingly curved shoulders or flanges 14 and 15 on the shank of the coupler, a slight clearance, however, being desirably provided, as illustrated, so that the bearing for the transmission of buffing 60 forces is normally between the curved edges of the shank loops and the curved walls of the pockets receiving said loops.

Associated with the coupler 1 is a yoke 16 of the vertical type with a hooded front end so that there are provided side walls 17 and 18 with a top wall 19 and a bottom wall 20. In the present embodiment, the walls 19 and 20 are merely extensions of the top and bottom arms of the yoke, the butt of the coupler 1 or swivel block portion 2 thereof preferably fitting snugly between the walls 17 and 18 of the yoke, and the width of said swivel block is preferably such that it is approximately that normally used with a standard horizontal yoke, so that the swivel butt coupler shown may be used interchangeably with 75

a horizontal yoke without undesirable side clearance. Inasmuch as this width is greater than the normal distance between the inner surfaces of the side walls of standard vertical yokes, the yoke 16 illustrated has its side walls more widely 80 spaced than those of a standard yoke, the dimensions of said yoke, however, being such that it is interchangeable with the standard yoke.

The pivot pins 4 shown in the embodiment of Figures 1, 2 and 3 are relatively short and 85 provided with heads 21 for limiting inward movement with respect to the swivel block whereby the inner ends of said pins, and particularly the upper pin, do not extend into the slot 22 and interfere with the key 23 which 90 serves for connecting the coupler stem 1 and the yoke 16. In order to retain the upper pin 4 in position, the upper flange 8 of the swivel block is preferably formed with a pair of lugs 24 and 25 95 grooved for guiding and retaining a preferably flat pin retainer 26. The retainer 26 is preferably apertured, as indicated at 27, for receiving the head 21 of the top pin 4, said head beyond the plate 26, when in position, being preferably apertured, as indicated at 28, for receiving a cotter or other retaining means 29 for locking the pin and retaining plate together and in position, thereby not only preventing undesired removal of the pin 4, but preventing it from dropping below its normal position and interfering with 105 the draft key 23.

The lower pin 4, which is desirably constructed to be identical with the upper pin 4, has its head 21 normally received in an aperture 30 in the supporting web or shelf 31 formed on the lower 110 flange 9 of the swivel block. Inasmuch as there is no tendency of the lower pin 4 to move upwardly, a cotter need not be used in the head aperture.

As an alternative, it will be understood that 115 a pin 4^a (reference being had to Fig. 8) of a height equivalent to the height of the associated swivel block 2^a only notched to receive the associated draft key, such as designated 23 in Figs. 1 and 2, may be employed instead of the pins 4 of 120 the first embodiment for providing a pivotal connection between said swivel block 2^a and the associated coupler shank 1^a. The head or upper end of the pin 4^a may be upset, as indicated at 32, to hold it in position, and, if desired, the 125 lower end may be similarly treated, which construction corresponds to that shown in my prior Patent No. 1,431,717, and makes it possible to eliminate any projections on the top and bottom flanges of the swivel block whereby it is possible, 130 if desired, to avoid upwardly and downwardly embossing or offsetting top and bottom walls 19 and 20 of the hooded end of the yoke, whereby the height of the coupler butt and cooperating yoke may be decreased.

If, however, the retaining means for the pin, such as shown in Figs. 1, 2 and 3, are desired, the general vertical dimension of the yoke 16 may be maintained standard by offsetting only the forward portions of the arms 19 and 20 140 which form the upper and lower walls of the hooded portion thereof along the longitudinal center line of the yoke an amount just enough to accommodate the pin-retaining means and the projecting head ends of the pins. Inasmuch as the retaining means on top and bottom of the swivel block 2 desirably extend corresponding distances from the corresponding flanges or webs of the swivel block, the amounts of offset of the arms of walls 19 and 20 are desirably equal, 150

thereby providing a symmetrical yoke which may be used with either arm uppermost.

It will be understood that the draft rigging arrangement shown is adapted for application

5 between normally spaced draft sills 33, and said sills are connected intermediate their ends by a combined back stop and rear draft lugs 34 preferably formed as an integral casting with a pocket 35 for receiving the rear end or loop 10 portion 36 of the yoke. For supporting the yoke, a carrier 37 is desirably provided extending between the sills 33 and connected to the lower flanges thereof in any desired manner, as by means of bolts and nuts 38. In order to restrain 15 the cushioning mechanism, diagrammatically indicated at 39, against forward movement when subjected to draft forces, front draft lugs 40 are provided and desirably connected to the webs of the sills 33 as by means of rivets 41, as illustrated particularly in Figs. 1, 2 and 3. Said draft lugs have the width of their shouldered portions 42 maintained generally to correspond with the width of standard draft lugs for use with vertical yokes, but are notched, as indicated 25 at 43, to provide the necessary clearance with respect to the side walls 17 and 18 of the yoke.

The draft lugs 40 are desirably formed integral as a combined casting with a striking portion 44 adapted to engage the horn 45 of the 30 coupler 1 and depending side portions 46 preferably strengthened along their front edges by transversely extending flanges or webs 47 and rearwardly extended along the sides of the sill webs as the slotted draft lug portions 40. The 35 draft lug shoulders 42 are desirably reinforced by forwardly extending tapering ribs or flanges 48 above and below the slots 49 which receive the key 23. The lower ends of the lug or shoulder portions 42 are desirably bent forwardly and 40 downwardly along the lower edges of the casting on the inner faces of the lug portions thereof, as indicated at 50, said flanges 50 tapering to merge into the lug portions, as shown most clearly in Fig. 6.

45 In order to compensate for the loss of this reinforcement, the outer faces of the lugs 40 along the lower edges thereof are strengthened by outwardly extending flanges 51 which may start from the side plates of the lugs where the 50 reinforcements 50 start to taper thereinto and increase in width to approximately the points where the reinforcements 50 merge into the lug plates, and from there, continue forwardly and downwardly to meet and merge with the sill tie 55 portion 52 of the casting.

In a similar manner, the casting is desirably reinforced on its outer faces by means of flanges 53 preferably tapering outwardly from the shoulder portions 42 to approximately opposite the 60 points where the reinforcing flanges 48 merge into the lug plates 40 and continue from there at preferably uniform size to either merge at the front ends of the slots 49, and from whence continue as single flanges 54 to join the reinforcing flanges 47, as shown in Fig. 6, or continue as spaced parallel flanges 53^a to join the reinforcing flanges 47^a, as shown in Fig. 7.

The striking casting portion 44 is desirably formed with a rearwardly extending web 55, the 70 rearmost portion of which is downwardly offset, as indicated at 56, to extend below and be connected with the center sill cover plate 57, the sides of said offset portion being bifurcated and extended to connect with the tops of the shoulder or lug portions 42. Said lug portions 42, in

addition to the connecting web portions 56, are desirably reinforced by triangular gusset portions 58 between said web portions 56 and the triangular reinforcements 48.

The coupler carrier or sill tie portion 52 of the casting desirably comprises an upper web 59 and depending flanges 60 preferably integral connecting the side portions 46, the outer flange 60 preferably being, in effect, a continuation of the flanges 47 of the side portions. In order to permit insertion and removal of the coupler stem 1, the intermediate part of the sill tie portion 52 is preferably downwardly offset, as indicated at 61, an amount sufficient to provide a space between it and the striking portion corresponding with the extreme vertical dimension of the butt of the coupler stem assembled. The side portions of the sill tie are preferably disposed at a slightly higher elevation to form abutments 62 for supporting the associated coupler carrier block 63, said abutments being desirably notched, as indicated at 64, to receive depending lug portions 65 on the carrier block 63 for holding said block in interlocked relation with respect to the casting 40. 100 In order to prevent undesired removal or loss of the block 63, the same is desirably retained in place by a bolt 66 extending entirely through said block and the side portions of the casting 40 and held in place by a head at one end and 105 a nut, preferably locked in position, at the other end.

In order to maintain the swivel block 2 of an overall width corresponding generally with that of a swivel block used with a horizontal yoke, 110 the intermediate portions of the sides of said block are preferably extended or bulged, as indicated at 67, which extensions lie in the vicinity of the slot 68, and thereby provide a somewhat greater bearing area between said swivel block 115 and the rear edge of the key 23. The depth of the extensions corresponds with the depth of the notches 43 in the lugs 40 or shouldered portions 42 thereof whereby adequate clearance is provided between the swivel block and said lugs. 120

The side walls 17 and 18 of the yoke hood desirably have their inner faces bulged or extended outwardly and are provided with lateral reinforcements on the outer faces thereof around the key slots therein, as indicated at 69, at 125 points corresponding with the bulges 67 on the swivel block and notches 43 in the draft lugs, the depth and thickness of said reinforcements or extensions 69 corresponding with the notches 43. On account of these extensions, the bearing 130 area between the key 23 and the rear ends of the slots in the walls 17 and 18 is maintained as in the standard vertical yoke, while, at the same time, the interior width of the yoke hood is increased, and because the exterior width of 135 the yoke hood is only locally increased adjacent the notches 43 in the draft lugs, the overall width of said lugs may be maintained to approximately correspond with those for a standard vertical yoke.

In order to provide for the rearward extension of the yoke slots to enable the key to move rearwardly with respect thereto, while not appreciably increasing the weight of the yoke, the side walls of said yoke are preferably extended 145 locally adjacent the rear ends of said yoke slots, as indicated at 70.

From a consideration of Fig. 2 particularly, it will be seen that the rear edges of the side walls 17 and 18 normally lie forwardly of the 150

rear faces of the draft lugs 40 or shoulders 42 thereof. This construction is provided because of the rearward movement of the yoke on buff. The relation of the coupler slot, the 5 yoke side wall slots, the sill and lug slots, is such, in the present embodiment, that when the coupler is subjected to buffing forces, it first moves rearwardly until the front edge of the slot 68 therein engages the front edge of the key 23, 10 whereupon the key moves rearwardly until the rear edge thereof engages the rear end of the slotted portions in the side walls 17 and 18 of the yoke hood, moving the yoke rearwardly so that the closed end 36 thereof moves toward the 15 back stop casting 34, and upon a full closure of the gear only normal clearance remains therebetween. At the same time, the extensions 70 on the yoke side walls move into the notches 43 in the draft lugs 40 and the forward portions 19 of the upper arms are likewise received in notches 71 in the upper ends of said shoulder portions 42, the lower arm of the yoke being desirably formed to lie below the lower ends of the shoulder portions 42 of the lugs. The 20 sides of the yoke adjacent the front ends of the slots 18 are desirably reinforced on the inner sides thereof, as indicated at 72, the sides of the coupler stem 1 being correspondingly notched, as indicated at 73, to receive said 25 reinforcements and provide the necessary clearance for a desired amount of relative angling of the coupler.

As a concrete example, illustrative but not limiting, of how the parts preferably move when 30 the coupler is subjected to buff, it might be stated that with a draft gear 39 having $2\frac{1}{2}$ " normal travel, the key slides in the coupler $\frac{5}{8}$ " and in the yoke $1\frac{1}{8}$ ", the yoke moving to the rear $\frac{1}{4}$ " upon full closure of the gear. If 40 the gear employed has a greater travel, of course, the yoke will move to the rear a correspondingly greater distance.

The foregoing embodiment of my invention may be employed when the longitudinal center 45 line of the coupler and connected yoke is disposed at normal elevation with respect to the draft sills, or as a concrete example, illustrative but not limiting, when said center line of the connected coupler yoke is disposed 7" from the 50 tops of 12" draft sills, or from the bottom surface of the associated sill cover plate. If the coupler and connected yoke are raised, as has been contemplated, until the longitudinal center line thereof is at the same elevation as the 55 neutral axes of such draft sills, or, as a non-limiting example, only 6" from the tops thereof, it is necessary to modify the construction of the top portion of the yoke hood and adjacent portion of the swivel block if the desirable results heretofore pointed out are to be accomplished, such modification being necessary, as 60 will be understood, in order to avoid interference between the top of the yoke hood and the sill cover plate.

65 Referring now to the modification of my invention illustrated in Figs. 9 to 12, inclusive, a construction is there shown in which the longitudinal center line of the coupler and connected yoke has been raised, as indicated in 70 the preceding paragraph, so that it corresponds in elevation with the neutral axes of the draft sills, that is, the center line of draft corresponds with the center lines of strength or neutral axes of the connected draft sills.

75 In the present embodiment, as in the previous

embodiment, the coupler stem 1^b is of the swivel butt type having a swivel block or butt portion 2^b connected to the coupler shank by pivotal means 3^b which, in the present embodiment, desirably takes the form of a one-piece pin which 80 extends through the shank loops or rearwardly extending flanges or webs 5^b and 6^b on the coupler stem and intercalated flanges or webs 7^b, 8^b and 9^b on the swivel block. The engaging edges of the parts are preferably constructed 85 as in the preceding embodiment, so that provision is made for the transmission of draft and buffing forces while allowing for the desired angling or pivotal motion therebetween.

Associated with the coupler stem 1^b is a yoke 90 16^b of the vertical type with a hooded front end provided with side walls 17^b and 18^b, preferably reinforced, and otherwise constructed approximately as in the preceding embodiment. Connecting the upper and lower edges of said side 95 walls is a top wall 19^b and a bottom wall 20^b, said walls being extensions of the top and bottom arms of the yoke 16^b, the butt of the coupler 1^b or swivel block portion 2^b thereof preferably fitting snugly between the walls 17^b and 18^b with 100 the width of the swivel block proportioned to properly fit between the side walls of the yoke, as in the preceding embodiment, so that said swivel block may, if desired, be used interchangeably with a standard horizontal yoke without 105 undue side clearance.

The pivot pin 3^b is preferably of uniform section through the major portion of its length, but is notched adjacent the intermediate portion thereof, as indicated at 74, to receive the 110 associated horizontal draft key 23^b, and the lower end thereof is reduced in section, as indicated at 21^b, and normally received in a preferably flat pin retainer 26^b, the edges of which are held in place between a pair of angular 115 lugs 24^b and 25^b, preferably extending from the lower flange 9^b of the swivel block.

The coupler stem 1^b and swivel block 2^b are desirably connected together by means of the pin 3^b prior to insertion in place with respect to 120 the yoke, as by dropping said pin 3^b upon the retainer plate 26^b with the reduced section 21^b passing through an aperture in said plate, whereupon the pin and plate may be locked together by means of a cotter 29^b, if desired, although it will be understood that this is not essential, as the parts will be held together by gravity. The advantage of the present construction over that of the first embodiment is that it avoids any extension on the top flange of the 130 swivel block whereby, although the height of the swivel block may generally correspond with that of the first embodiment, yet by eliminating the pin retaining means at the top the overall height may be so reduced that the top wall 19^b 135 of the hooded section of the yoke may be formed as a continuation of the top arm of the yoke and disposed at the same elevation without any bulging, as in the previous embodiment, whereby it will be appreciated that the relative elevation 140 of the coupler and connected yoke may be correspondingly raised, or to the position where a center line corresponds with the neutral axes of the associated draft sills. The lower wall 20^b of the yoke is, of course, bulged downwardly, as 145 in the preceding embodiment, to accommodate the pin retainer lugs 24^b and 25^b, and the extension 21^b of the pivot pin.

As in the preceding embodiment, the associated coupler and yoke may be employed be- 150

tween normally spaced draft sills and used with a combined back stop and rear draft lugs formed as in the preceding embodiment. For supporting the yoke, a carrier may be provided, as 5 in the preceding embodiment, and supported from the lower flanges of the sills. In order to restrain the cushioning mechanism, diagrammatically indicated at 39^b, against forward movement when subjected to draft forces, a combined 10 striking casting with integral sill tie member and slotted front draft lugs may be employed, as in the preceding embodiment, suitably modified, however, because of the raising of the parts.

As an alternative, I may employ draft lugs 15 40^b separate from the striking casting and sill tie member 44^b and connected to the inner sides of the sills 33^b, as by means of rivets 41^b. The width of the stop shoulders or flanges 42^b of said draft lugs 40^b preferably corresponds with 20 that of the draft shoulders or flanges 42 of the preceding embodiment, said flanges or shoulders being correspondingly notched, as indicated at 43^b, to accommodate the swivel block and yoke side wall reinforcements, as previously explained 25 in connection with the first embodiment. The lug shoulders or flanges 42^b, as in the preceding embodiment, are desirably reinforced by tapering flanges or gussets 48^b, 50^b and 58^b, the forward portions of the slotted draft lugs 40^b being 30 desirably connected by common rivets 75 to the side wall portions 46^b of the combined striking casting and sill tie member 44^b.

It will be noted that the webs of the draft sills are embraced between the rearwardly extending side portions 46^b of the combined striking casting and sill tie member 44^b and the associated draft lugs 40^b, the side wall portions 46^b being bifurcated and extended above and below the key receiving slots 49^b in said draft 40 lugs.

The striking casting and sill tie member 44^b is desirably formed with a rearwardly extending web or flange 55^b, the rearmost portion of which is desirably strengthened by an up-turned flange 45 56^b braced to the web 55^b by means of triangular gussets 57^b and desirably connected to the vertical flange 76 of the end sill 77, as by means of rivets 78. This construction compensates for the necessary decrease in height of the striking 50 face of the casting due to the raising of the coupler and yoke.

The combined casting 44^b, as in the previous embodiment, desirably has the sides 46^b connected by an integral sill tie portion 52^b, preferably formed as in the preceding embodiment, but correspondingly raised in accordance with the raising of the coupler and yoke, a removable carrier block 63^b of similar construction and similarly connected to said casting being also 60 desirably provided.

Although the sills in the present embodiment are shown as Z-shaped, rather than as channels, it will be understood that either Z- or channel-shaped sills may be employed, as desired, in connection with either embodiment. The in-turned flanges of the sills 33^b in the present embodiment are shown connected by a cover plate 57^b. Except as specifically described, the present embodiment may correspond substantially with the 70 first embodiment.

From the foregoing disclosure, it will be seen that I have devised an articulated coupler stem and vertical yoke combination in which the parts are so designed that the swivel block or 75 butt of the coupler may have an overall width

substantially corresponding with, although it may be slightly less than, that normally employed with a horizontal yoke or one with widely spaced side arms, whereby the key bearing area need not be substantially decreased. The 80 slots in the connected members are so proportioned that the yoke has some rearward movement when the coupler is subjected to buffing forces whereby the slotted side walls thereof normally lie forwardly of the draft lug stop shoulders.

The stop shoulders are designed to have an overall width corresponding with that employed with a standard vertical yoke and rigid stem coupler combination, whereby the front follower bearing area is not appreciably reduced, the side walls of the yoke hood are extended rearwardly of the ends of the slots therein locally with respect to said slots to maintain the desired strength, and the draft lug shoulders are notched to receive said extensions upon rearward movement of the coupler and associated yoke, said yoke side walls not only being extended rearwardly, but reinforced by lateral extensions fitting in the lug notches for maintaining the desired key bearing area. The draft lugs may be formed separate or integral with the striking casting and sill tie member and reinforced, not only by inner tapering ribs above and below the key slots, but by corresponding outer ribs extending to the front end of the combined casting and outer ribs extending along the lower edge of the lugs to the sill tie member. On account of the aforementioned improvement, the swivel butt coupler employed may be interchangeable 110 for use with either a horizontal or vertical yoke, the vertical yoke employed may be interchangeable with the standard or normal vertical yoke, and the draft lugs are of a width corresponding with that of normal draft lugs, said construction 115 being possible on account of the notching and local reinforcing of the parts, as previously explained.

Although I have described preferred embodiments of my invention, it will be understood that 120 modifications may be made within the spirit and scope of the appended claims.

I claim:

1. In railway draft rigging, in combination with draft sills, a hooded vertical yoke formed with key slots, a coupler stem fitting therein and formed with key slots, slotted draft lugs connected to the inner faces of said sills and provided with stop shoulders, a key connecting said coupler and yoke and received in the yoke, coupler stem and draft lug slots, and cushioning mechanism embraced between said coupler stem and yoke, the slots in said coupler stem and yoke providing for coupler stem travel with respect to the yoke less than the permissible travel of the 125 mechanism under the action of buffing forces, the slots in the draft lugs being extended rearwardly of the normal position of the key an amount sufficient to permit full compression of said cushioning mechanism, so that the yoke is 130 caused to move rearwardly upon full compression of the mechanism until the rear edge of the hood thereof approaches the plane of the lug stop shoulders.

2. In railway draft rigging, in combination with draft sills, a hooded vertical yoke, a coupler stem fitting therein, and slotted draft lugs connected to the inner faces of said sills and provided with stop shoulders normally engaged 145 by associated cushioning mechanism, the over-

- all width of the yoke hood adjacent the slots therein being greater than the distance between the innermost portions of the stop shoulders, the rear edge of the yoke hood being normally disposed forwardly of said stop shoulders, said stop shoulders being notched, and the widened portion of the yoke hood moving into said notched portions of the stop shoulders when the coupler is subjected to buffing forces. 80
3. A coupler stem with a swivel block pivotally connected to the rear end thereof, said stem and block being slotted to receive a horizontal key, the width of said block being increased locally adjacent said slot to the rear end thereof to present flat side faces of maximum spacing for use with a yoke with widely spaced side arms, said block being decreased in width above and below said slotted portion to adapt it for use also with a vertical yoke, the side walls of which are spread locally to take the enlarged slotted portion of the swivel block. 85
4. A front draft lug comprising a main web adapted for connection to an associated sill and slotted for receiving a draft key, a flange extending inwardly from said web along substantially the full height thereof and functioning as a stop shoulder, that portion of said flange adjacent the rear end of said slot being reduced in width to receive corresponding reinforcements on an associated yoke. 90
5. In combination with the draft sills of a car, a pair of front draft lugs each comprising a main web adapted for connection to an associated sill and slotted for receiving a draft key, a flange extending inwardly from each web along substantially the full height thereof and functioning as a front stop shoulder, that portion of said flange adjacent the rear end of said slot being reduced in width to receive corresponding reinforcements on an associated yoke. 95
6. In railway draft rigging, in combination with draft sills, a yoke with transversely spaced walls adjacent its forward end, a coupler stem fitting therebetween, means connecting said coupler and yoke, and draft lugs connected to the inner faces of said sills and formed with stop shoulders adapted to be engaged by cushioning mechanism, the width of said yoke over said walls being greater than the distance between the innermost portions of said stop shoulders, the rear edges of said walls being normally positioned forward of said shoulders, said stop shoulders being notched to receive portions of said yoke walls when moved rearwardly under the action of buffing forces. 100
7. In railway draft rigging, in combination with draft sills, a coupler stem fitting therebetween, a swivel block pivoted to the rear portion of said stem, said stem and swivel block being slotted to receive a draft key, said swivel block being formed with lateral porjections ex- 105
- tending rearwardly from said key slot and serving to increase the key bearing area, a yoke having a hooded forward end with side walls spaced laterally to correspond with the width of the swivel block over said projections for receiving the same therebetween, and lugs connected to said sills and provided with front stop faces adapted for engagement with an associated follower, said yoke having slots normally registering with the coupler slots for receiving a connecting draft key, and the portions of said yoke defining rear ends of said slots being normally disposed forwardly of said front stop faces. 110
8. In railway draft rigging, in combination with draft sills, a coupler with a two part stem fitting therebetween and comprising a butt portion pivoted to the rear portion of the coupler shank, said stem being slotted to receive a draft key, said butt portion being formed with projections on the sides extending rearwardly from said key slot, a yoke having a hooded forward end with side walls spaced to correspond with the nominal width of the butt portion and with its inners surfaces bulged locally to receive said projections, projections on the outer surfaces of the yoke side walls approximately corresponding with the butt portion projections, said side walls having slots for receiving the draft key and said projections serving to reinforce the walls around the rearmost portions of said slots; said slots being extended rearwardly of the normal position of the draft key an amount less than the rearward travel of the coupler upon buffing movement, and lugs connected to said sills and provided with front stop faces adapted for engagement with an associated follower, said lugs having their inner edges spaced a distance less than the width of the yoke over its projections and provided with notches to receive said projections upon rearward movement of 115 said yoke. 115
9. A yoke having a hooded front end provided with two pairs of oppositely disposed walls, a pair of such walls being bulged locally along their central portions, the walls normally lying in upright positions having slots elongated rearwardly from the normal position of the rear edge of an associated draft key to enable said key to move rearwardly with respect thereto under the action of buffing forces, said walls being extended locally around the rear ends of said slots to permit said elongation without appreciably increasing the weight of the yoke. 120
10. A draft lug comprising a web portion adapted for connection to an associated draft sill and slotted for receiving a draft key, and a stop portion extending from said web portion and formed with a notch intermediate the ends thereof to provide clearance with respect to an associated yoke. 125
